UNITED STATES PATENT OFFICE.

WILLIAM HACKETT, OF OAKLAND, CALIFORNIA, ASSIGNOR OF ONE-HALF TO
STEPHEN W. BAND, OF OAKLAND, CALIFORNIA.

LOCKING-BOLT.

1,385,001.

Specification of Letters Patent. Patented July 19, 1921.

Application filed March 15, 1920. Serial No. 365,985.

To all whom it may concern:

Be it known that I, WILLIAM HACKETT, a citizen of the United States, and resident of the city of Oakland, at No. 680 (32nd) 5 Thirty-second street, in said city, county of Alameda, and State of California, have invented a new and useful Locking-Bolt, of which the following is a specification.

My invention relates to an improved locking bolt especially adapted in use as a means for holding or clamping plates or the like together without the use of the customary threaded bolt structures commonly employed for this purpose.

15 The primary object of the invention is to provide means which may be conveniently used for permanently or temporarily clamping plates or the like and the existing novelty renders the same especially adapted in 20 connection with ship building where it is desirable to clamp two or more plates together preparatory to riveting or otherwise fixing them together.

25 The accompanying drawing illustrates the preferred manner of reducing the invention to practice:

In said drawing Figure 1 is a side elevation of the device.

30 Fig. 2 is a front elevation; Fig. 3 is a plan view;

Fig. 4 is a longitudinal section on the line 4—4, Fig. 3.

Fig. 5 is a cross section on the line 5—5 Fig. 3.

35 Fig. 6 is a perspective view of one form of locking pin.

Fig. 7 is another form of locking pin and

Fig. 8 is a cross section of another form of wedge and rocking block.

40 Referring to the drawing in detail A and B represent plates with which the device may be used as a means for clamping them together either temporarily or permanently. The plates, especially those used in ship building are usually provided with rivet openings at spaced intervals along their edges or in other places in the body thereof. Sometimes the overlapping edges of the plates are clamped together and then again

45 the two or more thicknesses of plates are fixed together. At any rate in using the device the bolt 1 is passed through two or more registering openings in the plates with the head 2 thereof providing a bearing on the 5 underside of the lowermost plate. The op-

posite end of the bolt is preferably constructed with a vertical slot or recess 3 made to receive a pin or the like 4 which according to Fig. 6 and as shown in association with the other parts of the device, has a 60 thickness of at least two different dimensions produced by cutting away a portion of the pin for a part of its length to leave the shoulder 5. The end of the pin is also constructed with an abutment 6 while the opposite end is provided with a T-head 7.

That form of pin shown in Fig. 7 is more applicable where the device is to be used as a permanent fixture and for this reason the same is constructed with a recess 8 leaving 70 the ends of greater thickness than the middle portion. Both forms of pins are adapted to be inserted in the recess 3 and in this manner confine the washer 9 on the bolt as well as the rocking block 10 both of which 75 have openings through which the bolt is passed. 11 represents a wedge which is adapted to be introduced between the top one of the plates A and B and the rocking block 10 to effect the desired clamping of 80 the plates. Any number of washers such as 9 may be used to build up the space between the plate A and the key 4 so that the wedge 11 may coöperate with the rocking block 10 to produce the desired results.

85 It should be noted that the opening through the rocking block 10 is slightly off center or in other words, eccentric with the vertical axis of the block, the purpose of which will now be described. The wedge 11 is a bifurcated member made to straddle the bolt 1 and a cross piece 12 is arranged to prevent the wedge from sliding off of the bolt should the device be used in a horizontal position. In accordance with that construction of wedge and rocking block shown in 90 Figs. 1 to 5 inclusive, both legs 13 and 14 of the wedge 11 which straddle the bolt are provided with a rabbeted edge as at 15 and with notches or teeth 16 arranged therein, 100 made to receive the fingers 17 of the rocking block 10.

95 The rocking block 10 is constructed with downwardly presented flanges 18 which terminate at one end in the fingers 17. These 105 flanges are arranged to bridge the wedge in order that the notches or teeth 16 therein may be made accessible to receive fingers 17. It should be noted that the rear of the block 10 is constructed with a cam face or 110

beveled off portion as at 19 so that the same normally only contacts with the wedge at the pivot point 20, see Fig. 4. With the opening through the block 10 offcenter and when the device is in use the force exerted on the block by the wedge will tend to maintain the fingers 17 engaged in the notches or teeth 16 of the wedge. In this connection, it should be noted that the key 4 is presented in the recess 3 of the bolt with its width of greatest thickness in use.

To release the device by driving pin 4 through the recess until its greatest thickness in width has been driven through the recess a blow inserted by a hammer or the like to the top of the block 10 at a point to the right of the pivot point 20 will rock the block on its pivot point and disengage fingers 17 from the teeth or notches 16 in the wedge. The wedge can then be removed which will permit the key being withdrawn and rocking block 10 and washer 9 removed. In effecting the clamping action of the plates with the device it should be noted that the farther the wedge is driven home the more positive will be the engagement of the fingers 17 with the notches or teeth 16.

In reducing the invention to practice, it will not be necessary to rabbet the wedge 11 and in this connection, attention is called to Fig. 8 wherein the wedge is shown with the legs 13 and 14 plain across the top, and to accommodate the rocking block 10 to this form instead of constructing the same with the downwardly presenting flanges 18, it is made of an equal thickness with the exception of the back portion which must be beveled off as in the other form to effect the rocking action described. It should be considered that further changes such as this may be resorted to without departing from the spirit of the invention.

Inasmuch as there will be considerable strain on the shank of the bolt 1 I will prefer to taper the end of the same for a part

of its length; for instance, from the lower end of the recess 3 toward the end. This will prevent burring which may possibly be caused by the strain as mentioned on the key. It should be considered that the tapered effect will only be present on two sides of the shank; for instance, on opposite sides of the opening to the recess.

I claim:

1. A locking bolt provided with a shank having a head at one end with its opposite end made to coöperate with a locking element, said shank adapted to be passed through two or more plates to be clamped together with the said plates confined thereon by said locking element, a block having an opening, said shank adapted to be passed through said opening for confining the block on the shank, and a slotted wedge having teeth on opposite sides of its slot, said wedge adapted to straddle the shank of the bolt between said block and said plates, with means on said block engaging the teeth of the wedge for maintaining the wedge in clamping relation with the plates.

2. A locking bolt, provided with a shank having a head at one end and a recess at its opposite end, a key made to engage said recess, said shank adapted to be passed through two or more plates to be clamped together with the said plates confined thereon by said key, a rocking block also confined on said shank and a wedge having teeth along its sides adapted to be presented between said block and the said plates, with the ends of said block engaging said teeth for maintaining the wedge in clamping relation with the plates.

3. A locking bolt as set forth in claim 2 and in which the rocking block has a beveled under surface; whereby the same may be rocked on the wedge to disengage the edge from the teeth of the wedge.

WILLIAM HACKETT
